SKI BINDING

Felix Tavi, New York, N. Y.

Application February 28, 1946, Serial No. 650,791

9 Claims. (Cl. 280—11,35)

1

This invention relates to a ski binding. One of the objects of this invention is to provide a new and improved ski binding. Another object is to provide a construction of the above character which is simple, practical, and thoroughly durable. Another object is to provide a construction of the above character, the manufacture of which will be economical both from the standpoint of labor and materials used. Another object is to provide a construction of the above character in which the structural elements are so disposed as to attain a high degree of strength without heavy construction. Another object is to provide a construction of the above character by means of which a ski boot may be securely fastened to a ski and at the same time permit a maximum of freedom of movement of the boot with respect to the ski. Another object is to provide a construction of the above character by means of which a ski boot may be fastened to or unfastened from a ski in a minimum of time and with a minimum of effort. Other objects will be in part obvious and in part pointed out herein-after.

The invention accordingly consists in the features of construction, combinations of elements, and arrangements of parts, all as will be illustratively described herein, and the scope of the application which will be indicated in the following claims.

Referring now to the drawings in which is shown one of the various possible embodiments of this invention,

Figure 1 is a side elevation of a ski boot fastened to a ski by the ski binding;

Figure 2 is a view similar to Figure 1 with the binding in an unfastened position;

Figure 3 is a top plan view of the ski binding mounted on a ski;

Figure 4 is a staggered longitudinal vertical section on an enlarged scale taken on the line 4—4 of Figure 3;

Figure 5 is a staggered vertical transverse section on an enlarged scale taken on the line 5—5 of Figure 4;

Figure 6 is a horizontal section taken on the line 6—6 of Figure 2;

Figure 7 is a vertical section on an enlarged scale taken on the line 7—7 of Figure 3 with the binding in an unfastened position;

Figure 8 is a longitudinal vertical section taken on the line 8—8 of Figure 9;

Figure 9 is a transverse vertical section on an enlarged scale taken on the line 9—9 of Figure 1, certain parts being removed for purposes of clarification; and,

2

Figure 10 is a transverse section on an enlarged scale taken on the line 10—10 of Figure 2.

Similar reference characters refer to similar parts throughout the several views of the drawings.

As conducive to a clearer understanding of certain features of this invention, it might here be pointed out that certain difficulties have been experienced with ski bindings now in use. One of the major difficulties lies in the fact that it is difficult and time consuming to fasten and unfasten the boot to a ski. This is important because a large number of the people now using skis find it desirable to frequently fasten and unfasten their ski bindings. Thus ski bindings should be so constructed that the user may fasten and unfasten his ski bindings rapidly and easily at all times. Another difficulty experienced with many bindings now in use is that they do not permit a maximum of freedom of the ski boot with respect to the ski. Another major difficulty experienced with many ski bindings now in use lies in the fact that they do not securely connect the boots to the skis and thus do not give the user precision control of his skis. This connection should be one in which freedom of movement of the heel vertically with respect to the ski is permitted while movement of the heel transversely of the ski is prevented. A further difficulty with many bindings now in use lies in the fact that the user must kneel down to fasten or unfasten his ski bindings with his bare hands. A still further difficulty with bindings now in use lies in the fact that it is difficult and time consuming to mount them upon a pair of skis. It is accordingly another object of this invention to overcome the above-mentioned difficulties as well as many others.

In general, the ski binding includes a pair of locking plates and force applying members, generally indicated at 10 and 11 (Figures 3 and 4) pivotally mounted on a metal framework by pivot pins 12 and 13. Locking plates 10 and 11 are moved into and held in locking position by a resilient lever, generally indicated at 14, and act through U-shaped leaf springs, generally indicated at 15 and 16 (Figures 3, 4, 5 and 7), which form force applying parts serving to grip the welt 17 (Figures 4 and 5) of the boot, generally indicated at 18 (Figure 1). When locking plates 10 and 11 are moved into locking position, they, acting through plates, which form heel cable actuating levers, generally indicated at 19 and 20, draw forwardly on the heel cable, generally indicated at 21 (Figures 1 and 3), causing it to

grip the heel of boot 18 and move the boot forwardly into its proper position between the toe irons. Lever 14 is held in locked position by a catch, generally indicated at 22 (Figures 1 and 4), and when it is desired to release the ski binding, catch 22 is pivoted in a clockwise direction which permits lever 14 to move upwardly. This releases the pressure exerted by plates 10 and 11 through springs 15 and 16 upon the welt of the boot and also moves the heel cable 21 rearwardly into engagement with a catch 23 (Figure 2). At this time the heel may be lifted upwardly and the boot may be moved rearwardly out of the ski binding.

The framework of the ski binding includes a pair of toe irons, generally indicated at 24 and 25 (Figures 1, 3 and 4), and a base plate, generally indicated at 26. Toe irons 24 and 25 include base portions 24a and 25a and vertical flange portions 24b and 25b. The base portions 24a and 25a overlie the ski 27 and extend beneath base plate 26 to which they are connected by screws 28 and 29 (Figures 3 and 5). Screws 28 and 29 extend through transverse slots 30 and 31 in base plate 26, thus permitting movement of toe irons 24 and 25 transversely with respect to the base plate. Toe irons 24 and 25 are connected to the ski 27 by two pairs of screws 32 and 33 which extend through holes in base plate 26 and openings 34 and 35 in the base portions 24a and 25a of the toe irons. These openings are of substantially greater width than the diameter of the shank of screws 32 and 33 and thus permit angular as well as transverse adjustment of the toe irons with respect to the base plate 26. Thus the vertical flange portions 24b and 25b of the toe irons may be adjusted to fit boots of different widths and shapes. When the toe irons have been adjusted to fit the tapered toe portions of the ski boots with which they are to be used, then screws 28, 29, 32, and 33 are tightened, holding the toe irons in their adjusted positions.

To aid in maintaining the toe irons in their adjusted positions, the front and rear corners 36, 37, 38, and 39 (Figures 3 and 5) of the base portions of each toe iron are turned down and sharpened. Thus, when screws 32 and 33 are tightened, these corners are embedded into ski 27 and prevent movement of the toe irons with respect to the ski.

Base plate 26 extends longitudinally of ski 27 throughout the length of the ski binding and is positioned over the base portions of toe irons 24 and 25 and a catch plate, generally indicated at 40. Catch 23 (Figures 1 and 3) is secured to catch plate 40 and extends upwardly through a slot 26a in base plate 26 extending longitudinally thereof. Catch plate 40 has slots 42, 43, 44, and 45 therein extending longitudinally thereof in alignment with holes in base plate 26 through which the screws 46 pass which connect the rear end of the base plate to the ski. This permits plate 40 and thus catch 23 to be adjusted longitudinally of the base plate 26 when screws 46 are loosened so that catch 23 may be adjusted to engage heel cable 21 when the ski binding is unfastened (Figure 2). In addition to screws 32 and 33, the center and forward portions of base plate 26 are connected to ski 26 by screws 47, 48, and 49 (Figures 3 and 4). Screws 47 aid in maintaining toe irons 24 and 25 in their adjusted positions by creating tension against the toe irons because there is a space between base plate 26 and the top of ski 27

forwardly and rearwardly of the base portions of the toe irons. This permits base plate 26 to be drawn downwardly with respect to the base portions of the toe irons so that it clamps the toe irons in their adjusted positions.

The toe of boot 18 (Figure 1) is connected to the ski binding and thus to the ski by locking plates 10 and 11 which act through springs 15 and 16 to engage the welt of the boot. As locking plates 10 and 11 are similar in construction, details of construction will be limited to locking plate 10 (Figures 4 and 7). This locking plate is pivotally mounted upon the flange portion 24b of toe iron 24 by pivot pin 12 and its lower edge engages the upper leg 15a of U-shaped flat spring 15. The lower leg 15b of spring 15 extends beneath a serrated strip 50 (Figure 7) and is connected to the bottom portion 24a of toe iron 24 by rivets 50b. The lower edge 10a of plate 10 is so shaped that it acts through corners 10b and 10c to press the upper leg 15a of spring 15 downwardly upon the welt 17 of the ski boot. When the locking plate 10 is in a locked position, corner 10c is positioned nearer the ski than corner 10b and thus the major gripping action is attained between corner 10c and the base portion 24b of toe iron 24. The rear end of the upper leg of spring 15 curves upwardly to engage the rear portion of locking plate 10 (Figure 7). Thus, when plate 10 is in locking position, corner 10b (Figure 4) presses downwardly upon the rear portion of spring leg 15a causing the spring to press downwardly upon and grip a substantial portion of welt 17.

As the locking plate 10 is spaced from the welt at its rear end and grips the welt through spring 15, without adjustment locking plate 10 acting through spring 15 will securely grip different welts having a substantial variation in thickness.

Referring to Figure 7, it will be noted that the forward end 50a of serrated strip 50 curves upwardly and that the strip is secured to toe iron 24 adjacent its rear end. As strip 50 is resilient, when locking plate 10 presses the welt 17 of the ski boot against the strip, the forward end of the strip reacts to drive its teeth into the bottom of the welt. To supplement the action of the plate 10 and spring 15 in gripping the welt of the boot, the teeth on strip 50 slant forwardly, and thus, when the locking plate is in locked position, prevent the welt from moving rearwardly with respect to the ski.

As pointed out hereinabove, locking plate 11 is substantially similar in construction to locking plate 10. This plate is pivotally connected to flange 25b of toe iron 25 by pivot pin 13 (Figures 1 and 3). This plate coacts with a spring 16 similar in construction to spring 15 and a serrated strip 51 (Figure 5) to grip the welt on the left-hand side of the ski boot.

Plates 10 and 11 are moved into and out of locking position by resilient lever 14 (Figure 4). Lever 14 is made of spring rod and the ends of its rear portion, which are U-shaped, extend downwardly into vertical holes 10d and 11d (Figures 3, 4 and 5) in plates 10 and 11. The rear ends of lever 14 extend downwardly into vertical holes in plates 10 and 11 and are rotatably secured therein in any suitable manner, such as by punching a portion of each plate into annular recesses 14e and 14f (Figure 5) formed in the portions of lever 14 extending downwardly in holes 10d and 11d. This permits the rear ends of lever 14 to turn in the holes in plates 10 and 11 as the lever is raised and lowered and thus

accommodate itself to different angular positions of the locking plates.

Referring to Figure 4, the legs 14a and 14b of the U-shaped portion of lever 14 extend forwardly and upwardly from plate 10 when it is in a closed position (Figure 4) to clear the toe portion of the ski boot and thence extend downwardly to the foot of the U-shaped portion of the lever. The two sides of lever 14 then extend forwardly to a juncture point (Figure 3) at the forward end of lever 14. Intermediate between the foot of the U-shaped portion of lever 14 and its forward end, a rod 52 extends transversely across the lever between the two sides thereof and is secured thereto in any suitable manner, such as by welding.

Lever 14 is so shaped longitudinally that when the lower edges of locking plates 10 and 11 engage the welt of the boot, its forward end is still positioned a substantial distance above the ski. Thus, when it is moved downwardly so that bar 52 is engaged by catch 22, lever 14 exerts a resilient downward pressure in a counterclockwise direction, as viewed in Figure 4 upon plates 10 and 11 and thus upon the welt of the ski boot. Lever 14 is so constructed that it gives in two directions after the locking plates engage the welt of the boot. The two portions of the lever which substantially parallel the ski (Figure 4) bend longitudinally of the ski and the downwardly extending sections of the U-shaped portion of the lever give toward the toe of the ski boot. This results in achieving the resiliency of a lever of much greater overall length than lever 14 which is of material aid in gripping the welt of the ski boot.

Catch 22 is pivotally mounted by a pivot pin 54 which extends transversely across and is connected to a pair of flanges 26b and 26c (Figures 3 and 4) extending upwardly from the sides of the forward end of base plate 26. With welts of different thicknesses, the effective length of lever 14 becomes shorter or longer depending on the thickness of the welt being gripped and thus bar 52 moves longitudinally with respect to the ski when it moves into latching position with respect to catch 22. Thus, to properly position catch 22, pivot pin 54 is adjustable longitudinally with respect to flange portions 26b and 26c. To insure that pivot pin 54 retains its adjusted position, it is preferably made in the form of a bolt having a square neck 54b. The bolt extends through aligned longitudinal slots in flanges 26b and 26c. The upper and lower edges of one of these slots are provided with teeth 55 and 56 (Figures 1 and 8), opposed notches between these teeth being spaced from each other a distance equal to diametrically opposed corners on the neck portion 54b of pivot pin 54 (Figure 8). Thus, when the pivot pin 54 is passed through the slots, the neck portion of the pivot pin engages teeth, thus preventing longitudinal movement of the pivot pin with respect to the slots. The pivot pin is preferably held in position by a nut 57 which bears against a lock washer 58 and base plate flange 26c. Thus pivot pin 54 may be readily adjusted longitudinally of the base plate to properly position catch 22 so that it engages bar 52.

Catch 22 includes a forwardly extending tongue portion 22a which when the catch is in an open position is engaged by bar 52 (Figure 2) as it moves downwardly. Catch 22 is held in an open position, when it is unlatched because its rear end portion 22b is heavier than the forward portion of the catch moving it in a clockwise

direction, as viewed in Figure 4, to the position it occupies in Figure 2. When lever 14 is moved downwardly, bar 52 strikes the upper surface of tongue portion 22a and throws catch 22 in a counterclockwise direction. When pressure is immediately released upon lever 14, bar 52 moves upwardly and is caught beneath a downwardly extending hook 22c (Figure 4) positioned on catch 22 above its pivot pin. When it is desired to release catch 22, downward pressure is applied to a punch plate 53 (Figures 3 and 4) on the forward end of lever 14. When bar 52 moves downwardly, the holding pressure on hook 22c is released and the weight of the rear portion 22b of catch 22 pivots it in a clockwise direction (Figure 4) moving hook 22c out of the path of bar 52. Thus when pressure on the forward end of lever 14 is released, bar 52 does not catch upon hook 22c. Lever 14 is thus free to move up and as it does so, assisted by the action of springs 15 and 16 on locking plates 10 and 11, the welt is released.

Punch plate 53 is so formed that the user may fasten or unfasten his ski bindings by using the end of his ski pole. Thus, the user does not have to bend down on his knees in wet snow or slush whenever he desires to put on or take off his skis. Referring to Figure 3, it will be noted that there is a recess 22d (Figures 3 and 4) in the rear portion 22b of catch 22. This is provided so that if snow or ice prevents the catch from operating, the user may open the catch by pressing downwardly on the rear portion of the catch with his ski pole thus freeing the binding. Thus, the user can at all times remove his skis without touching his bindings with his hand, and at times this is of major importance such as after an accident when it is not possible for the skier to reach his bindings with his hands.

A pair of recesses 10e and 11e are formed in the forward upper portions of each of plates 10 and 11. The leg portions 14a and 14b of lever 14 bridge these recesses and then extend through notches 10f and 11f (Figures 3 and 4) formed in the upper surface of the forward portion of plates 10 and 11. Recesses 10e and 11e form openings to permit a toe strap 60 (Figures 2 and 3) to be mounted upon the legs 14a and 14b of lever 14. It will be noted that strap 60 is moved downwardly by lever 14, and thus grips the toe of the ski boot.

When lever 14 (Figures 1 and 2) is moved downwardly to a latched position, it acts through plates 10 and 11 and plates 19 and 20 (Figures 1 and 3) to move heel cable 21 forwardly into engagement with the heel 18a (Figure 1) of boot 18. Plates 19 and 20 are pivotally connected to locking plates 10 and 11 by pivot pins 61 and 62 (Figures 2 and 7). Plates 19 and 20 are also connected to the flange portions of toe irons 24 and 25 by rivets 63 and 64 which extend through arcuate slots 65 and 66 in toe iron flange portions 24b and 25b. Slots 65 and 66 are embossed outwardly and the head portions of pivot pins 63 and 64, such as head portion 64a (Figure 10), of these pins are flanged to fit the slots. A pair of links 67 and 68 (Figures 2, 5, and 7) are pivotally connected to flange portions 24b and 25b (Figures 2 and 7) by pivot pins 69 and 70 which are radially positioned with respect to arcuate slots 65 and 66. The other ends of links 67 and 68 are pivotally connected by pivot pins 63 and 64 to plates 19 and 20. When lever 14 is moved toward a locked position, the points 62 and 63 at which locking plates 10 and 11 are connected

to plates 19 and 20 move forwardly and downwardly as plates 10 and 11 are pivotally connected to the toe irons 24 and 25 below the points of connection between the two pairs of plates. At the same time because the heads of pivot pins 63 and 64 are following slots 65 and 66 which curve forwardly and downwardly and because of links 67 and 68, pivot pins 63 and 64 are moving forwardly. As pivot pins 61 and 63 are pivotally connected to plate 19 and pivot pins 62 and 64 are pivotally connected to plate 20, plates 19 and 20 move forwardly with respect to ski 27 when lever 14 is moved to a locking position.

The heel cable 21 consists of a pair of rods 71 and 72 which are pivotally connected to plates 19 and 20. The forward end of each of these rods preferably extends outwardly (Figure 3) and is shaped to form wing portions 71a and 72a (Figures 1 and 7). Holes 78 and 79 are provided in plates 19 and 20 which have upwardly and downwardly extending slots opening thereto. When it is desired to attach a rod to a plate, it is vertically positioned with respect to the plate to which it is to be connected, the wing portions are passed through the slots, and then the rod is moved rearwardly and downwardly. When it is in a downward position, the wing portions 72a and 72b prevent the ends of the rod from being drawn inwardly through the holes in the plate to which they are pivotally connected. Slots 78 and 79 are positioned adjacent the rear ends of the flange portions 24b and 25b of the toe irons and also slant forwardly (Figures 1 and 7), and the wing portions on rods 71 and 72 are longitudinally aligned with the rods. Thus to attach the heel cable, the plates 19 and 20 must be moved rearwardly or to an unfastened position as otherwise the heel cable cannot be slanted forwardly to align the wing portions of the rods with slots 78 and 79 because the rods 71 and 72 would strike the toe irons and locking plates 10 and 11. Thus when the skis are removed, if the binding is placed in a fastened position, the heel cable cannot become accidentally disconnected from the binding.

The rear portion of the heel cable is in the form of a coil spring 73 to which rods 71 and 72 are connected by a pair of metal fittings 74 and 75 (Figures 3 and 6). These metal fittings are similar in construction and each is threaded on its exterior surface so that each fitting may be threaded into an end of spring 73. A thread hole, similar to hole 75a (Figure 6), extends through each of fittings 74 and 75 and the rear ends of rods 71 and 72 are threaded into these holes. When it is desired to adjust the heel cable with respect to the heel of a boot, spring 73 is adjusted toward and from the heel by disconnecting rods 71 and 72 from plates 19 and 20 and then turning rods 71 and 72 into or out of fittings 74 and 75. After the adjustment is made, rods 71 and 72 are again connected to plates 19 and 20 as described hereinabove.

To permit the heel cable to exert a downward pressure upon the heel, if such pressure is desired, plates 19 and 20 have holes 76 and 77 (Figures 1 and 7) therein positioned rearwardly and downwardly from holes 78 and 79 (Figures 2 and 7). Rods 71 and 72 may be connected to holes 76 and 77, and then when lever 14 is moved to a latched position, the heel cable 21 exerts a downward pull upon the heel of the boot.

When the lever 14 moves upwardly, it moves plates 19 and 20 rearwardly. Because of the

rigidity of rods 71 and 72 the spring portion 73 of cable 21 is moved beneath catch 23 (Figure 2). When the heel cable is so positioned as the grip upon the welt of the boot has been released, the heel may be raised and then the boot withdrawn rearwardly out of the ski binding.

Thus, in operation, when it is desired to fasten the ski binding, the toe is inserted into the binding so that the upper legs of springs 15 and 16 overlie the welt on the opposite sides of the toe of the boot (Figure 5). Next the heel portion of the boot is placed down in contact with base plate 26 and then lever 14 is moved downwardly. As the lever moves downwardly the heel cable first moves the ski boot forwardly into proper position between the toe irons and then locking plates 10 and 11 exert a pressure downwardly upon the upper legs of springs 15 and 16 firmly gripping the welt between the springs and serrated strips 58 and 51. It will be noted that the hook portion 23a of catch 23 is positioned above the ski, and thus when the cable leaves catch 23, it moves into engagement with the groove in the heel of the ski boot. This eliminates the necessity of raising the heel cable by hand each time the binding is fastened and together with catch 22 makes a binding which may be operated simply by pressing downwardly on punch plate 53 with a ski pole. At the same time heel cable 21 moves forwardly (Figure 1) so that coil spring 73 resiliently engages the heel 18a of the ski boot. Then lever 14 is bent downwardly so that bar 52 (Figure 4) actuates catch 22 to latch lever 14 in a downward position.

To release a ski boot from the ski binding, punch 53 is pressed downwardly. This permits catch 22 to pivot to an unlatched position so that lever 14 is free to move upwardly. As lever 14 moves upwardly, it moves plates 10 and 11 in a clockwise direction releasing pressure on the upper legs of springs 15 and 16 and acting through plates 19 and 20 to move the heel cable 21 rearwardly into engagement with catch 23. At this time the ski boot may be removed from the ski binding. It will be noted that punch plate 53 (Figures 2 and 4) has a downwardly extending portion 53a which protects catch 22 so that snow or other objects cannot pass beneath the forward end of lever 14 to move catch 22 to an unlatched position. It also prevents any foreign objects, such as the ring of a ski pole or a branch of a tree from being caught under the end of lever 14.

The ski binding shown is so constructed that it may be adjusted to fit any size ski boot. As described hereinabove, toe irons 24 and 25 (Figure 3) may be moved transversely with respect to the ski and their angular position may also be varied so that they fit the toe portion of the boot. As springs 15 and 16 and all of the other mechanism for securing a ski boot is mounted on the vertical flange portions 24b and 25b of the toe irons, the springs and associated mechanism are properly positioned when the toe irons 24 and 25 are adjusted so that they correctly engage the welt of the ski boot.

To adjust the heel cable 21, rods 71 and 72 (Figures 1 and 3) are disconnected from plates 19 and 20 and then the rods are turned into or out of the metal fittings 74 and 75 secured to the forward ends of coil spring 73. After they have been adjusted, they are again connected to plates 19 and 20 in the high or low position depending on the direction the user prefers to have pull exerted upon the heel of his ski boot. After the

cable has been adjusted, then the catch plate 48 is adjusted longitudinally with respect to base plate 26 so that the hook portion 23a of catch 23 (Figure 2) engages and holds spring 23 in a raised position when the ski binding is in an unfastened position.

Thus, a ski binding has been disclosed by means of which a ski boot may be fastened or unfastened to a ski in a minimum of time and with a minimum of effort. Furthermore, the ski boot is mounted in such a way that the user is permitted a maximum of freedom of movement while at the same time the user has complete control of his skis at all times because his ski boots are securely connected to his skis. Thus, a practical and efficient ski binding has been disclosed in which the above mentioned objects as well as many others are successfully accomplished.

As many possible embodiments may be made of the mechanical features of the above invention and as the art herein described might be varied in various parts, all without departing from the scope of the invention, it is to be understood that all matter hereinabove set forth, or shown in the accompanying drawings is to be interpreted as illustrative and not in a limiting sense.

What is claimed is:

1. In a ski binding for fastening a ski boot to a ski, in combination, toe iron means, a pair of locking members pivotally mounted on said toe iron means, means for moving said members downwardly toward the welt of a ski boot into a position where said locking members exert substantial downward pressure upon the welt of said boot, and a pair of resilient serrated strips secured to said toe iron means, each of said strips being positioned beneath one of said locking members, the forward portions of said strips curving upwardly, whereby when the sole of said boot is pressed into contact with said strips said strips resiliently press their serrations into engagement with the sole of said boot.

2. In a ski binding for fastening a ski boot to a ski, in combination, toe iron means, a pair of locking members pivotally mounted on said toe iron means above the welt of said boot on both sides of the toe thereof, spring means positioned between said locking members and said welt, said spring means distributing the pressure of said locking members over substantial areas of the welt of said boot, and a pair of resilient serrated strips secured to said toe iron means, each of said strips being positioned beneath one of said locking members, the forward portions of said strips curving upwardly, whereby when the sole of said boot is pressed into contact with said strips said strips resiliently press their serrations into engagement with the sole of said boot.

3. In a ski binding for fastening a ski boot to a ski, in combination, toe iron means, a pair of locking members pivotally mounted on said toe iron means, a pair of U-shaped springs extending longitudinally of said ski positioned on opposite sides of said ski binding, the foot of each of said U-shaped springs being positioned forwardly, one leg of each of said springs being positioned beneath the sole of said boot and mounted on said toe iron means, and the other of each of said legs being positioned between the welt of said boot and one of said locking members, and means for moving said locking members downwardly against the upper legs of each of said springs to lock the welt of said boot between the leaves of said springs.

4. In a ski binding for fastening a ski boot to a ski, in combination, toe iron means, a pair of U-shaped springs extending longitudinally of said ski, means connecting the lower legs of said springs to said toe iron means on opposite sides of said ski binding, the foot of each of said U-shaped springs being positioned forwardly, one leg of each of said springs being positioned beneath the sole of said boot and the other of each of the legs of said springs being positioned above the welt of said boot, and the means for pressing the upper leaf of each of said springs downwardly, whereby the welt of said boot is gripped between the leaves of said spring.

5. In a ski binding for fastening a ski boot to a ski, in combination, toe iron means, a pair of locking members pivotally mounted on said toe iron means, a pair of U-shaped springs extending longitudinally of said ski positioned on opposite sides of said ski binding, the foot of each of said U-shaped springs being positioned forwardly, one leg of each of said springs being positioned beneath the sole of said boot, and the other of each of said legs being positioned between the welt of said boot and said locking members, means connecting said lower legs to said ski binding, a resilient lever connected to said members, said resilient lever pivoting said locking members downwardly against the upper legs of each of said springs to lock the welt of said boot between the leaves of said springs, and catch means for holding said lever in locked position.

6. In a ski binding for fastening a ski boot to a ski, in combination, toe iron means, a pair of locking members pivotally mounted on said toe iron means, a pair of U-shaped springs extending longitudinally of said ski positioned on opposite sides of said ski binding, the foot of each of said U-shaped springs being positioned forwardly, one leg of each of said springs being positioned beneath the sole of said boot, and the other of each of said legs being positioned between the welt of said boot and said locking members, means connecting said lower legs to said ski binding, means for moving said locking members downwardly against the upper legs of each of said springs to lock the welt of said boot between the leaves of said springs, and a pair of serrated bars each positioned above the lower legs of one of said springs, the serrations on each of said bars extending upwardly.

7. In a ski binding for fastening a ski boot to a ski, in combination, toe iron means, a pair of locking members pivotally mounted on said toe iron means, a pair of U-shaped springs extending longitudinally of said ski positioned on opposite sides of said ski binding, the foot of each of said U-shaped springs being positioned forwardly, one leg of each of said springs being positioned beneath the sole of said boot, and the other of each of said legs being positioned between the welt of said boot and said locking members, means connecting said lower legs to said ski binding, a resilient lever connected to said members, said resilient lever pivoting said locking members downwardly against the upper legs of each of said springs to lock the welt of said boot between the leaves of said springs, catch means for holding said lever in locked position, a heel cable, and means connecting said heel cable to said locking members, said heel cable being drawn forwardly to engage the heel of said boot as said locking members are pivoted into locked position.

8. In a ski binding for fastening a ski boot to a ski, in combination, toe iron means, a pair of

locking members pivotally mounted on said toe iron means, a pair of U-shaped springs extending longitudinally of said ski positioned on opposite sides of said ski binding, the foot of each of said U-shaped springs being positioned forwardly, one leg of each of said springs being positioned beneath the sole of said boot, and the other of each of said legs being positioned between the welt of said boot and said locking members, means connecting said lower legs to said ski binding, means for moving said locking members downwardly against the upper legs of each of said springs to lock the welt of said boot between the leaves of said springs, a pair of serrated bars each positioned above the lower legs of one of said springs, the serrations on each of said bars extending upwardly, a heel cable, said heel cable including a spring portion for engaging the heel of said ski boot, and a pair of rods threaded into the forward ends thereof, means connecting each of said rods to one of said locking members, said rods being drawn forwardly to engage the heel of said boot as said locking members are pivoted into locked position.

9. In a ski binding for gripping the top and bottom edge portions of each side of a boot welt and sole to a ski, in combination, laterally and angularly adjustable opposing side supporting members extending upwardly from the ski beside the sole, force-applying members respectively supported from each side supporting member at first and fixed pivots, each force-applying member having a force-applying part overlying the welt of a boot positioned between the side members for applying a clamping force to the top of the boot welt therebelow, a resilient lever secured to and extending forwardly from each force-applying member for pivoting the force-applying member to apply through the force-applying part the said clamping force, a heel cable, heel cable actuating levers respectively pivoted on said force-applying members at second and movable pivots spaced forwardly from said first pivots, toggle links respectively secured to said heel cable actuating levers at third and movable pivots spaced below and forwardly from said second

pivots, and secured with respect to the respective side-supporting members at fourth and fixed pivots spaced below said first, second and third pivots, said heel cable being connected to each heel cable actuating lever at connecting points positioned rearward of said second, third and fourth pivots, whereby force-applying movement of said force-applying members move said second pivots and said heel cable actuating levers downwardly and said toggle links move said third pivots forwardly to move the connecting points of said heel cable actuating levers downwardly and forwardly to cause said heel cable to move forwardly against the boot heel to move said boot into binding position as said force-applying member is moved into force-applying position, the connecting point of each heel cable actuating lever being positioned generally rearward of the ball portion of the ski boot and generally in the horizontal plane thereof, whereby movement of the heel and heel cable upwardly from the ski pivots the heel cable actuating levers about the second pivots to cause the toggle links to raise the second pivots and the force-applying members against the action of said resilient lever to relieve the clamping force.

FELIX TAVI.
